UNITED STATES PATENT OFFICE.

GARABED HAROUTUNIAN AND SARKIS HAROUTUNIAN, OF CHELSEA, MASSACHUSETTS.

DISH-HOLDER.

1,184,851.

Specification of Letters Patent. Patented May 30, 1916.

Application filed August 18, 1915. Serial No. 46,035.

To all whom it may concern:

Be it known that we, GARABED HAROUTUNIAN, a citizen of the United States, and SARKIS HAROUTUNIAN, subject of 5 Armenia, both residing at Chelsea, in the county of Suffolk and State of Massachusetts, have invented an Improvement in Dish-Holders, of which the following is a specification.

10 Our present invention relates broadly to new and useful improvements in holders for receptacles, and has particular reference to the provision of a detachable holder for plates and other shallow receptacles, having 15 a relatively wide, flat marginal portion.

One of the principal objects of our present invention is to provide a detachable holder of the character specified which is of simple construction and may, therefore, be 20 cheaply manufactured, will be durable and efficient in service, and may be quickly attached to or removed from the plate or other receptacle.

Another object of our invention is to construct a detachable holder, which is of ornamental design, and which is adjustable to adapt it to hold plates or like receptacles having marginal portions of varying 25 angles.

30 The above and incidental objects of a similar nature which will be hereinafter more specifically treated, are accomplished by such means as are illustrated in the accompanying drawings, described in the following specification, and then more particularly pointed out in the claims which are appended hereto, and form a part of this application.

With reference to the drawings wherein 40 there has been illustrated the preferred and several embodiments of our invention;—Figure 1 is a top plan view of a plate illustrating our detachable holder applied thereto. Fig. 2 is a section on line 2—2 of 45 Fig. 1. Fig. 3 is a section on the line 3—3 of Fig. 1. Fig. 4 is a detail view in section illustrating particularly by dotted lines the manner in which the slope or angle of the rim-portion of the holder may be 50 adjusted to accommodate plates or other receptacles, the rim-portions of which extend at varying angles to the horizontal. Fig. 5 is a top plan view illustrating the modified form of holder applied to a plate; and, 55 Fig. 6 is a bottom plan view of the device as shown in Fig. 5.

In Figs. 1, 2, and 3, the rim-portion of the holder designated as an entirety by the letter A, is shown as applied to a plate B, to form in effect an extension of the rim-portion C thereof. At this point it is to be explained that while the detachable-holder has been designed particularly for use in connection with plates, saucers, and the like, it may be employed in connection 60 with receptacles of different types as long as these receptacles are provided with marginal portions or rims of such nature that my detachable-holder may be properly secured thereto. The rim-portion A consists 65 essentially of a body-ring 10, and a reticular band arranged thereon. The ring 10 is formed from drawn wire of medium gage, and relatively stiff, so that it will retain its shape during various adjustments 70 of the band. The band is preferably formed from a single strand of drawn wire of relatively small gage, bent to produce a plurality of overlapping loops or convolutions 11, which define an annular band, as 75 shown in Figs. 1 or 2. These convolutions 11 are here shown as held against circumferential movement upon the ring 10 by means of a securing-wire 12, which is wound helically about the ring 10 in such 80 manner as to secure the adjacent sides of the convolutions to the ring. This securing-wire 12, while holding the convolutions on the ring 10, yet permit of a rocking movement thereof, see Fig. 4, wherein it will be 85 seen that the convolutions are conjointly turned about the ring 10 as an axis, thereby to vary the pitch or slope of the band. Thus the band may be adjusted to accommodate it to receptacles having rims 90 arranged to extend at different angles with respect to the horizontal. Handles 13 are or may be applied to the body-ring 10 at diametrically opposite portions. As a means for detachably securing the rim-portion to 95 a plate, we employ an extensible ring 14, and a plurality of contractile springs 15. The ring 14 is formed from a single strand of wire, bent to form an annular series of loops 16, the ends of the wire comprising the ring being twisted or otherwise secured together. The ring is adapted to be arranged on the bottom of the plate with its loops extended downward. The inner ends of the springs 15 are provided with loops 100 105 or eyes 18, which engage said ring, and the outer ends of said springs are provided 110

with hooks 19, which engage the convolutions 11 of the rim-portion, see Fig. 1. Upon reference to Figs. 1 and 2, it will be apparent that the securing-ring 14 is applied to the basal flange 20 of the plate to snugly embrace the same, and that the springs being of similar length tend to exert a uniform pull, thus drawing the rim-portion and ring toward each other. When said members are drawn toward each other, the inner edge of the rim-portion will extend over and rest upon the upper face of the margin of the plate, thus holding the plate. The securing-ring 14 performs a further function in that its loops 16, when extended downward, act as supports for the plate and space the basal flange thereof above a table or other support for it. One of the particular features of importance of this preferred form of the invention is the adjustability of the convolutions to vary the slope or pitch of the detachable rim-portion, so that it may accommodate receptacles, the rims of which bear different angles to the horizontal.

In the modified form of our invention shown in Figs. 5 and 6, all of the features of construction of the preferred form are employed, and in addition thereto the inner and outer edges of the annular reticular rim-portion have secured to them rings 22 and 23. These rings 22 and 23 are or may be each formed from single strands of relatively light gage wire, bent to form a series of loops quite similar to the securing ring 14. These rings are secured by fine wires 24 and 25, respectively, to the convolutions of the rim-portion. Thus the convolutions of the rim-portion are maintained against relative movement, and may not therefore be adjusted to vary the slope or pitch of the band. In applying this modified form of detachable rim to a plate, the inner ring 22 is disposed upon the upper face of the plate rim, as in Fig. 5. These rings 22 and 23 impart stability, and also a decorative appearance to the detachable-holder.

We claim:—

1. A detachable-holder for plates and the like, comprising an annular substantially flat rim-portion arranged to surround the marginal portion of the plate, and its inner edge to extend over the top of said portion, and means associated therewith, arranged for engagement with the bottom of the plate.

2. A detachable-holder for plates and the like, comprising a relatively stiff body-ring and an annular band arranged thereon, its inner edge adapted to extend over the marginal portion of the plate, and means associated therewith, arranged for engagement with the bottom of the plate.

3. A detachable-holder for plates and the like, comprising an annular, substantially flat rim-portion arranged to surround the

marginal portion of the plate, and its inner edge to extend over the top thereof, and means connected with said rim-portion, in rear of its inner edge, at a plurality of uniformly-spaced intervals, and arranged for engagement with the bottom of the plate. 70

4. A detachable-holder for plates and the like, comprising an annular substantially flat rim-portion arranged to surround the marginal portion of the plate, and its inner edge to extend over the top thereof, a ring arranged for engagement with the bottom of the plate, and means to connect said ring at regularly spaced intervals with the rim-portion in rear of its inner edge. 75 80

5. A detachable-holder for plates and the like, comprising an annular rim-portion arranged to surround the marginal portion of the plate, and its inner edge to extend over the top thereof, an extensible ring arranged when contracted for engagement with the bottom of the plate, and means to connect said ring, at regularly spaced intervals, with the rim-portion, in rear of its inner edge. 85 90

6. A detachable-holder for plates and the like, comprising an annular rim-portion arranged to surround the marginal portion of the plate, and its inner edge to extend over the top thereof, a ring composed of wire bent to form a series of loops, arranged for engagement with the bottom of the plate, radially disposed members to connect said ring with the rim-portion, in rear of its inner edge. 95 100

7. A detachable-holder for plates and the like, comprising an annular band composed of wire, bent to form a series of overlapping convolutions arranged to surround the marginal portion of a plate, and its inner edge to extend over the top thereof, fastening-means therefor, and means connected with said band, in rear of its inner edge, arranged for engagement with the bottom of the plate. 105 110

8. A detachable-holder for plates and the like, comprising an annular band composed of wire, bent to form a series of overlapping convolutions arranged to surround the marginal portion of a plate, and its inner edge to extend over the top thereof, a body-ring, means for connecting said band to said body-ring, and means connected with said band in rear of its inner edge, arranged for engagement with the bottom of the plate. 115 120

9. A detachable-holder for plates and the like, comprising an annular band composed of wire, bent to form a series of overlapping convolutions arranged to surround the marginal portion of a plate, and its inner edge to extend over the top thereof, a body-ring, a strand wound helically around said body-ring and the adjacent sides of the convolutions of the band to connect the band to the body-ring, and means connected with said 125 130

band, in rear of its inner edge, arranged for engagement with the bottom of the plate.

10. A detachable-holder for plates and the like, comprising an annular rim-portion arranged to surround the marginal portion of the plate, and its inner edge to extend over the top thereof, said rim portion being adjustable to vary its angle relative to the horizontal, and means connected with said

10 rim-portion, in rear of its inner edge, arranged for engagement with the bottom of the plate.

11. A detachable-holder for plates and the like, comprising an annular band composed of wire, bent to form a series of overlapping convolutions arranged to surround the marginal portion of a plate, and its inner edge to extend over the top thereof, a ring

arranged at one side of said band, and means to connect adjacent convolutions of 20 said band to said ring, admitting of a rocking movement of the convolutions on the ring to vary the angle of the band relative to the horizontal, and means connected to said band, in rear of its inner edge, and arranged for engagement with the bottom of 25 the plate.

In testimony whereof, we have signed our names to this specification, in the presence of two subscribing witnesses.
